UNITED STATES PATENT OFFICE

EDWIN M. BASSLER, OF WAUSAU, WISCONSIN, ASSIGNOR TO D. J. MURRAY MANUFACTURING COMPANY, OF WAUSAU, WISCONSIN, A CORPORATION OF WISCONSIN

VENTILATING APPARATUS

Application filed April 26, 1928. Serial No. 273,069.

The invention relates primarily to improvements in cook stove ventilators and has for its object the provision of a simple, compact and efficient attachment for cook stoves, 5 adapted and arranged to effect thorough ventilation thereof and removal of burnt products of combustion and odors of cooking food therefrom.

Another object of the invention is the provision of an improved fan and motor arrangement for such constructions.

Another object of the invention is to provide an improved fan and motor construction for such installations so arranged that they 15 will occupy a space of minimum size and at the same time, provide means for cooling the motor.

Still a further object of the invention is to provide a motor driven fan in which the fan and motor are combined in such manner that they may be assembled in a space of minimum size.

Other objects will appear hereinafter.

The invention consists in the various features, combinations of features and details of construction hereinafter described and claimed.

The invention will be best understood by reference to the accompanying drawings 30 forming a part of this specification, in which—

Fig. 1 is an enlarged sectional view of a motor driven fan embodying my invention and improvements taken substantially on line 35 1—1 of Fig. 4;

Fig. 2 is a view from the right side of Fig. 1, the casing being shown in section and the fan guard being removed;

Fig. 3 is a detail section taken substantially on line 3—3 of Fig. 1;

Fig. 4 is a front view, partially in section, showing my improved fan as applied in use to a ventilating attachment for a usual form 45 of gas cook stove and which embodies my invention as it relates to such attachments;

Fig. 5 is a side view of the same;

Fig. 6 is an enlarged sectional view taken through the suction chamber forming part 50 of the attachment;

Fig. 7 is a section taken substantially on line 7—7 of Fig. 6; and

Fig. 8 is an enlarged section taken substantially on line 8—8 of Fig. 4.

Describing the invention, in the first instance, as it relates to improvements in motor driven fans and with particular reference to Figs. 1 and 2, said fan comprises a casing 10 provided with a securing flange 11 adapted and arranged to be secured by screws 12 60 around an opening 13 provided in the back plate 14 of an ordinary gas cook stove, as indicated.

The fan casing 10 is provided with an opening 15 adapted and arranged to receive 65 the motor 16, as indicated, said motor being further secured in said recess by means of screws 17, if desired. The motor 16 is a usual electric motor equipped with a central shaft projecting, as indicated, through the opening 13 in the back sheet 14 of the stove.

Secured to the projecting end of the motor shaft 18 is the central hub 19 of a centrifugal fan of special construction. As shown, said fan is made with integral arms 20 and extend into the rim chamber 22 of the fan casting 10, and formed on which within said chamber, are vanes or blades 21. The fan blades 21 may have their outer tips or edges 23 bent slightly forward to increase their air propelling action, and the inner edges of said fan blades are reinforced by flanges 24, as shown. By this arrangement as the fan blades revolve in the direction of the arrows, Fig. 2, air will be drawn through the opening 13 into the chamber 22 of the fan housing by the centrifugal action of the fan blades.

Referring now particularly to Figs. 4 to 8, the fan casing 10 is provided with a tangential air discharge connection 25 to which is attached the lower section 26 of a ventilating flue pipe 27. Said flue pipe is provided with an enlarged suction chamber 28 and the section 26 is provided with an ejector 95 nozzle 29 extending upwardly through the chamber 28, as best shown in Fig. 6.

A branch ventilating pipe 30 leads, as shown, from the suction chamber 28 into the oven 31 of the stove, said branch pipe being 100

provided with a damper 32 for obvious purposes. By this arrangement, as the air is forced upwardly through the ventilating flue 27, a suction of air is induced through the branch pipe 30, thereby thoroughly ventilating the oven 31 when the damper 32 is open.

The air entering the chamber 22 of the fan housing will also serve to cool the motor.

The opening 13 and the fan blades are covered and protected by a dome-shaped, perforated guard plate 33 secured in place, as shown, by means of the screws 12, which also secure the casing 10 to the back sheet 14.

The shelf 34 is located at a higher level than the opening 13 and is provided with an extension 35 slidably mounted on guide rods 36, whereby said shelf may be extended over the open burners of the stove when desired. By this latter arrangement the products of combustion arising from the open heating devices of the stove and odors, as of cooking foods, will be, in a measure, trapped by the extension shelf and therefore more readily withdrawn by the suction action of the fan, the escape into the room of said products of combustion and odors being thereby prevented.

By this arrangement a highly efficient and compact ventilating attachment is provided for ordinary gas and other similar stoves. In such constructions, in order to economize space, it is usually desirable to place the stove as close as possible to a wall of the kitchen, the arrangement being such as to mount the electric motor and the cooperating suction fan in the smallest possible lateral space, thereby permitting the positioning of the stove close to a wall of the kitchen, as desired.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

I claim:

1. Ventilating apparatus comprising a supporting plate provided with a ventilating opening; a fan casing secured to one side of said plate around said opening and provided with a central motor space and a surrounding fan chamber having an opening registering with said ventilating opening; a motor supported in said motor space with its shaft protruding through said plate opening; fan blade supports secured to the protruding end of said shaft and extending thence into said fan chamber through said openings; and fan blades on said supports and operating in said fan chamber.

2. Ventilating apparatus substantially as specified in claim 1 which also comprises a

skeleton guard enclosing the protruding end of the motor shaft and the fan blade supports.

3. Ventilating apparatus comprising a supporting plate provided with a ventilating opening; an annular fan casing secured to one side of said plate around said opening and provided with a re-entrant flange at the edge of the ventilating opening and secured to said supporting plate around said opening, said fan casing extending inwardly beyond the periphery of the opening and being itself provided with an opening registering with said first mentioned opening, thereby providing for annular access to said fan casing; a motor supported within said fan casing with its shaft protruding through said plate opening; fan blade supports secured to the protruding end of said shaft and extending thence into said fan chamber through said openings; and fan blades on said supports and operating in said fan chamber.

In witness that I claim the foregoing as my invention, I affix my signature this 20th day of April A. D. 1928.
